SAWMILL CARRIAGE SETWORK

Theodore H. Best, Diamond Springs, Calif.

Application February 11, 1938, Serial No. 189,999

3 Claims. (Cl. 143—120)

This invention relates to sawmills, and particularly to the setwork of log carriages.

At present, the rotation of the set shaft, by means of which the head blocks are advanced, is usually controlled by a friction mechanism. The operation of such a mechanism however is hard to control to the nicety necessary for the desired accuracy of advance of the head blocks, and as a result, the thickness of the board sawed from the log with the travel of the carriage, is apt to vary considerably from the intended thickness to which the setworks control is set by the operator. As a result, considerable wastage is incurred in subsequently reducing the over thick boards to the proper dimension, or valuable time is lost in segregating those boards which are too thin from those of the correct dimension.

It is therefore the principal object of my invention to practically eliminate the possibility of an inaccurate advance of the head blocks by the provision of electrically controlled structure by reason of which the rotation of the set shaft is positively halted as soon as the head blocks have reached the position for which the control lever is set.

A further object is to provide a structure for the purpose which can make use of the standard setworks and its control mechanism with but slight alterations or additions being necessary, although it is possible to make such control mechanism much lighter than is now feasible.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Figure 1 is a side elevation, partly in section and somewhat diagrammatic, of my improved setworks control structure as applied to the set shaft.

Figure 2 is a diagram of the circuits employed in connection with the structure.

Referring now more particularly to the characters of reference on the drawing, the log carriage is indicated at 1, the setworks being mounted on the carriage adjacent one end.

Extending along the carriage above the floor 2 is the set shaft 3, the rotation of this shaft in one direction or the other controlling the advance

or retraction of the head blocks in the usual manner.

Upstanding from the floor 2 is the control stand S which comprises a pedestal 4 in which a vertical shaft 5 is journaled, this shaft being operatively connected to shaft 3 by bevel gearing.

Fixed on the shaft 5 adjacent its upper end is the usual ratchet wheel 7 which cooperates with a fixed graduated plate 8 thereabove, said plate being as usual marked in inches or fractions thereof.

The setting lever 9 is turnable on shaft 5 immediately under the ratchet wheel, and on its outer end carries an upstanding pawl and handle 10. This is normally disengaged from the ratchet wheel, but as usual is adapted to be swung by the operator into locking engagement with the wheel at any point in its circumference, so as to rotate with the wheel in a head-block advancing direction. The above parts are all standard in the setworks ordinarily used in the mills, and I do not change this structure in any way.

The lever 9 however now carries a contact 11 on its front face, which is adapted to engage a cooperating contact 12 disposed in the path of the lever and mounted on a stop block 13 rigid with the stand S. A wire 14 from the contact 11 is electrically connected with a collecting ring 15 on the shaft 5, which ring is also electrically connected with a stationary wire 16. Another wire 17 is connected to contact 12, which is of course insulated from the stand, as is contact 11.

Secured on the set shaft 3 adjacent one end and ahead of the gearing 6, is an exposed friction pulley 18 and a brake drum 19 which is engaged by a magnetic brake device 20, the brake unit being enclosed in a housing 21. The shaft 3 at said one end is aligned with a separate drive shaft 22, driven from an electric motor 23 with a reduction gear box 24 therebetween. The adjacent ends of the shafts 3 and 22 are provided with the cooperating parts of a normally disengaged or deenergized magnetic clutch indicated at 25 and 45 enclosed within a housing 26.

The motor is connected to a jack shaft 27 under the floor 2 by a belt drive 28, the jack shaft being parallel to and directly under shaft 3 and having adjacent one end a friction pulley 29 normally clear of but adapted to engage pulley 18. To allow of the necessary vertical movement of the jack shaft for such engagement, I interpose a flexible coupling 30 in the jack shaft just ahead of the pulley and beyond the fixed shaft bearings 55

31. The pulley 29 is lifted by the operator into engagement with the pulley 18 by means of a rocking lever unit 32 mounted under the floor 2 and extending lengthwise of shaft 27. At one end, the lever engages a yoke and collar unit 33 on shaft 27 adjacent the pulley 29, and at the opposite end is provided with an upstanding depressible stem 34 carrying a pedal 35 on its upper end positioned convenient to the operator stationed adjacent the control stand. A spring 36 preferably applied to unit 33 acts to positively hold the pulley 29 clear of pulley 18 when pressure on the pedal is removed.

15 The magnetic brake and clutch are designed to operate on direct current, whereas alternating current is frequently all that is available from the power lines leading to the mill. In this case, a D. C. generator 37, of sufficient capacity to supply the necessary current for the purpose, is 20 driven from the motor 23, which is constantly operating.

25 The wires 38 of the magnetic clutch are connected to the supply wires 39 from the generator and a normally open magnetic switch 43 is interposed in the wires 38.

30 The wires 41 from the magnetic coil 42 of the brake unit are also connected to the wires 39 and a normally open magnetic switch 43 is interposed in wires 41, one of the wires 44 from the magnet 40a of switch 40 is connected to one of the wires 39, while the other wire 44 is connected to one fixed contact 45 of a special switch, the other fixed contact 46 of which is connected to the other wire 39. This special switch is mounted 35 convenient to the operator at the control stand. The contacts 45 and 46 are horizontally spaced from each other, and are adapted to be bridged, to close the circuit, by a rocking contact blade 47 pivoted intermediate its ends in the switch box. 40 A push button member 48 projects upwardly from the end of the blade which is uppermost when the switch is open, while a similar member 49 projects upwardly from the opposite end of the blade. Associated with the member 49 below the blade is the core 50 of a solenoid coil 51, one end of which is connected to wire 17. The other end of the solenoid coil is connected to one of the wires 52 of magnet 43a of switch 43, the other wire 52 being connected to one supply 50 wire 39. The wire 16 is connected to the other supply wire 39, so that a circuit through the solenoid coil and magnet 43a is closed when the contacts 11 and 12 are engaged.

55 In operation, when it is desired to advance the head blocks, the setting lever 9 is engaged with the ratchet wheel at the desired point as determined by a reading against the fixed gauge plate 8. The button 48 is then depressed to cause the blade 47 to engage contacts 45 and 46. A circuit is thus obviously closed through the magnet 40a, causing switch 40 to be closed. A circuit is then closed through the magnetic clutch, causing shaft 3 to be driven from shaft 22. The shaft 5 and ratchet wheel are also rotated, causing the lever 9, which has been locked to the ratchet wheel, to be turned toward the stop block. The head blocks are now being advanced by the rotation of shaft 3.

70 As soon however as the contacts 11 and 12 engage each other with the rotation of the lever, a circuit is at once closed through the solenoid coil 51 and magnet 43a. The solenoid being thus energized, the core 50 is instantly pulled down, moving switch blade 47 to an open position and 75 breaking the circuit to magnet 40a. The switch

40 immediately opens, breaking the circuit to the magnetic clutch and causing the clutch 25 to be immediately disengaged. At the same time, the magnet 43a of switch 43 being now energized, the switch 43 is closed. This closes the circuit to the 5 brake, which is at once applied.

Since electrical apparatus acts almost instantaneously, the clutch releasing and braking action take place at the same time, preventing any possible coasting of the set shaft, and insuring its 10 halting at the point position necessary to give an accurate positioning of the head blocks corresponding to the initial setting of the lever 9.

15 It is of course to be understood that the magnetic brake is of a size and power such that it 15 will stop the set shaft the instant the brake is applied.

The solenoid remains energized as long as the contacts 11 and 12 are engaged, providing a safety feature against possible inadvertent or accidental depression of the starting button 48. When the lever 9 is pulled away from the contact 12 by hand, the circuits to the solenoid and brake are at once broken, but the switch blade 47 remains in an open position, and can only be closed 25 by another hand movement.

If it is desired to advance the head blocks without any accurate positioning thereof, the lever remains disengaged from the ratchet wheel, and the starting and stopping of the set shaft is controlled by hand depression of the buttons 48 and 49 respectively.

When it is desired to retract the head blocks, after the contacts 11 and 12 are separated, it is only necessary to depress pedal 35, bringing 35 pulleys 29 and 18 into engagement.

Since the jack shaft 27 is constantly driven from the motor in the same direction as the drive shaft 22, the set shaft will now be rotated in the opposite or retractive direction, such rotation continuing as long as the foot pressure is retained on the pedal.

From the foregoing description it will be readily seen that I have produced such a device as substantially fulfills the objects of the invention as 45 set forth herein.

While this specification sets forth in detail the present and preferred construction of the device, still in practice such deviations from such detail may be resorted to as do not form a departure 50 from the spirit of the invention, as defined by the appended claims.

Having thus described my invention, what I claim as new and useful and desire to secure by Letters Patent is:

1. A setworks control mechanism comprising with a set shaft, a rotatable setting lever and means to connect the lever to the set shaft for rotation therewith through any selected arc; a constantly turning drive shaft, a normally disengaged magnetic clutch between the drive shaft and set shaft, a normally open circuit for the clutch, a normally released magnetic brake associated with the set shaft, a circuit for said brake including a normally open switch, a hand switch to close the clutch circuit whereby to engage the clutch and rotate the set shaft and lever, another normally open circuit, means to close the brake circuit by the closing of said other circuit, switch contacts in said circuit closed by the arrival of the lever at the end of said selected arc, and means actuated by the closing of said other circuit to open said hand switch and including means to prevent reclosing of said hand switch until said other circuit is again open.

2. A structure as in claim 1, in which the hand switch includes a blade movable in one direction to close the switch and in the opposite direction to open the switch and said last named means comprises a solenoid coil interposed in said other circuit, and a core for the solenoid connected to the blade and disposed to cause the blade to be pulled in said opposite direction when the solenoid is energized.

10 3. A networks control mechanism comprising with a set shaft, a rotatable setting lever and means to connect the lever to the set shaft for rotation therewith through any selected arc; a constantly turning drive shaft, a normally disengaged magnetic clutch between the drive shaft and set shaft, a normally open circuit for the

clutch, a normally released magnetic brake associated with the set shaft, a circuit for said brake including a normally open switch, a magnet to close said switch, a normally open circuit for the magnet, a hand switch to close the clutch circuit whereby to engage the clutch and rotate the set shaft and lever, a switch in said magnet circuit comprising a contact on the lever and a fixed contact positioned in the path of movement of said lever contact to be engaged thereby with the rotation of the lever to the end of said selected arc whereby the magnet circuit will be closed and the brake circuit switch closed, and means actuated by the closing of said magnet circuit to also open the hand switch.
